UNITED STATES PATENT OFFICE.

JAMES H. DEXTER, OF BOSTON, MISSOURI.

DESIGN FOR A DISPLAY-BOARD.

SPECIFICATION forming part of Design No. 23,814, dated November 13, 1894.

Application filed September 25, 1894. Serial No. 524,111. Term of patent 7 years.

To all whom it may concern:

Be it known that I, JAMES H. DEXTER, of Boston, Barton county, Missouri, have invented and produced a new and original Design for Display-Boards, of which the following is a full, clear, and exact description, reference being had to the accompanying drawing, forming a part hereof.

My object is to produce a new design for display boards, and the leading features of the same are the upright columns, the horizontal partitions connecting the same, and the arch mounted upon the said columns.

Said design is illustrated by the drawing hereunto annexed, in which 1, 1 designate two vertical columns, which are fluted longitudinally; being of the Corinthian style of architecture, and 2, 2 designate cap-stones thereon. These columns 1, 1 are connected by the horizontal base 3, and the arch 4 rests upon and connects the cap-stones 2. This arch is of ornamental configuration, being provided centrally at its upper side with the crown-like offset 5, and near each end with the hook- or horn-like projection 6. The face of said arch is also paneled, and the face of the annular flange thus formed is cross-hatched in the drawing to represent rough or bush-ham-

mered stone-work. Depending from the arch at points equally distant from its center, are two curved arms 7, which rest upon cap-stones 8 of the Corinthian columns 9—9, which are parallel with and divide the space between the columns 1, 1 into three equal spaces. The middle space is divided by the horizontal partitions 10, cross-hatched to represent bush-hammered stone-work, into the central space 11, the space 12 above, and the spaces 13, 14 and 15 below said central space. Similar horizontal partitions 10 divide the side spaces into the spaces 16, 17, 18, 19, 20, 21, 22 and 23, and the similar vertically elongated spaces 24—24 are formed between the arch and the topmost partition 10 of the middle space by the short vertical column 25, which is also of Corinthian style.

Having thus described my invention, what I claim is—

The design for a display board, substantially as herein shown and described. 50

In testimony whereof I affix my signature in presence of two witnesses.

JAMES H. DEXTER.
